UNITED STATES PATENT OFFICE.

GEORGE HENRY AIREY, OF PARIS, FRANCE.

APPARATUS FOR LOADING OR UNLOADING VESSELS.

SPECIFICATION forming part of Letters Patent No. 747,923, dated December 29, 1903.

Application filed September 18, 1902. Serial No. 123,893. (No model.)

To all whom it may concern:

Be it known that I, GEORGE HENRY AIREY, a subject of the King of the United Kingdom of Great Britain and Ireland, residing at 3
5 Rue Cernuschi, in the city of Paris, France, have invented new and useful Improvements in Loading or Unloading Vessels, of which the following is a specification.

This invention relates to improvements in 10 loading and unloading vessels, and in carrying it into effect I proceed in or in about the following manner, making reference to the accompanying drawings, wherein—

Figure 1 is a side view of the arrangement 15 on the delivering vessel; Fig. 2, a front view of part of Fig. 1; Fig. 3, a side view of the arrangement on the receiving vessel; Fig. 4, a side view, and Fig. 5 a front view, of a hook to be hereinafter described; and Fig. 6, a general view of the arrangement on the delivering and receiving vessels. Figs. 7, 8, and 9 are, respectively, side, front, and plan views 20 of details to be hereinafter mentioned.

On the delivering vessel *a* I provide a mast 25 *b*, having running on or within it a weight *c*, to which is attached one end of a wire rope or the like *d*, which passes over a pulley *e* and then through a sloping tube *f*, from whence it passes to and under a pulley *g* on the deck *h* 30 of the receiving vessel, and this pulley may be removable, so that it can be placed at any convenient part of the deck. The wire rope *d* is continued over a pulley or guide *i* at the top of a suitably stayed mast *j* on the receiving vessel and is finally attached to a weight *k*, running on or within the said mast *j*.

At the top of the mast *b* is a pulley or drum *l* and at the bottom is a similar pulley or drum *m*. Over the said pulleys or drums *l* and *m* 40 is passed an endless band *n*, the pulleys being at right angles to the pulley *e* and tube *f*, and guides may be provided to keep the band *n* in place as it passes along.

A chain or other contrivance may be used 45 instead of a band, and the drums *l* and *m* may be replaced by sprocket or polygonal wheels.

The drum *m* is rotated by any suitable motor or by hand.

Outstanding from the band *n* are a number 50 of guard-arms *o*, each curved toward the opposite side of the band to that to which they

are attached, and adjacent to each pair of the arms *o* is a carrier *p*, to each of which is detachably attached a bag *q* of the article being loaded or unloaded. The bags *q* are suspended from hooks *r*, having the downwardly-sloping releasing-arms *s* and an elevating-hook *t*, which is placed on the carrier *p*. The guard-arms *o* and carriers *p* are attached to the band *n* by sockets *r'*, riveted to the belt *n*. 60

It is essential to the steady conveyance of the goods that the hook *t* should be long and flat, so as to rest firmly on the carrier *p*, the bags being kept from swinging outward by the above-mentioned rods *o*. 65

Between the highest part of the releasing-hook *r* is a pulley *u* for facilitating the movement of the hook *r*, as will be presently described, and a snap-hook may be provided some distance below the hook *r* to keep the 70 hook from running off.

The operation is as follows, assuming the band *n* to be revolved by any suitable means: The bags of material *q* are suspended from the carriers *p* by the hooks *t* in such manner 75 that the downwardly-sloping arms *s* shall be inside the band *n* when the bags are being raised. When the pulleys *u* come in contact with the sloping tube *f*, (into which position they are guided by the sloping arms *s*.) the 80 bags *q* are lifted from the carriers *p* and the pulley *u* put on the tube *f*, whereupon the hook and bag *q* will run down the wire *d* and carry the goods to the receiving vessel. If desired, the weights *c* and *k* can be allowed 85 to run overboard or down a stay and, if preferred, multiplying tackle can be used, so as to provide for a longer wire *d*. The mast *b* may, if preferred, be erected on a quay or other position on shore instead of on the delivering boat *a*. 90

The object of the weights *c* and *k* is to permit the wire *d* to accommodate itself to any movement of the masts *b* and *j* caused by the rolling of the delivering and receiving vessels. 95

What I claim as my invention, and desire to secure by Letters Patent, is—

In means for loading and unloading vessels wherein the goods are run down an inclined rope from the delivering to the receiving vessel, an endless-band elevator; lifting-arms outstanding from the said endless band; an 100

inclined tube at the top of the elevator-mast through which passes the inclined rope; lifting-hooks to hang on the said lifting-arms on the endless band, the said hooks having a flat 5 overturned part to rest on the lifting-arms and an upstanding loop above the said flat overturned part and a downturned and outwardly-sloped arm by which the hook and its load are shunted from the lifting-arm on to the inclined

tube and from thence to the inclined rope, to substantially as hereinbefore described.

In testimony whereof I have signed my name to this specification in the presence of two subscribing witnesses.

GEORGE HENRY AIREY.
